137,880

DESIGN FOR A FORK OR OTHER ARTICLE OF FLATWARE

Philip Vitolo, Long Island City, N. Y., assignor to National Silver Company, New York, N. Y., a corporation of New York

Application March 6, 1944, Serial No. 112,787

Term of patent 14 years

(Cl. D54—12)

To all whom it may concern:

Be it known that I, Philip Vitolo, a citizen of the United States, residing in Long Island City, in the county of Queens, city and State of New York, have invented a new, original, and ornamental Design for a Fork or Other Article of Flatware, of which the following is a specification, reference being had to the accompanying drawing, forming a part thereof, in which:

Fig. 1 is a front elevation of a fork or other article of flatware embodying my new design: and

Fig. 2 is a side elevation thereof.

I claim:

The ornamental design for a fork or other article of flatware, as shown.

PHILIP VITOLO.
